SIGNORS TO PRATT & WHITNEY COMPANY, OF NEW YORK, N. Y., A CORPORATION OF
NEW JERSEY

GEAR-TOOTH-FINISHING MACHINE

Application filed November 26, 1927. Serial No. 235,866.

This invention relates to a gear tooth finishing machine and in particular to a machine for shaving or taking a finishing cut over the tooth curves of a gear by a tool moving in the direction of the rolling motion of the gear.

More particularly the invention relates to improvements in a machine of the type shown and described in the patent granted to Barnes No. 1,608,052, dated November 23, 1926.

An object of the present invention is to provide a machine in which the gear being finished is mounted on a spindle oscillating about a fixed axis and in which the tool or tools are moved back and forth in a straight line in timed relation to the oscillatory movements of the spindle.

Another object of the invention is to provide a cam locked to the spindle carrying the gear during the cutting portions of its oscillatory movements for effecting the reciprocating movements of the tools, the cam being formed so that the tools will pass over the profiles of the gear teeth to properly generate the curved tooth form.

Another object of the invention is to provide means for effecting feeding movement of the tools during operation and indexing movements of the spindle when the tools are out of contact with the gear blank to progressively cut the teeth during successive rotations of the blank.

Another object of the invention is to index the gear during the continued oscillatory movements of the spindle and reciprocatory movements of the tools, this indexing taking place while the spindle is rotating in one direction so that each of the gear teeth may be engaged successively by the tools during a revolution of the spindle without loss of time.

Another object of the invention is to provide means associated with the indexing mechanism to move the gear a slight distance away from a tool when the tool has reached the end of its cutting stroke over the tooth profile so that when the direction of rotation of the spindle and the movement of the tool is reversed the tool will not drag over the finished surfaces of the gear teeth.

Another object is to effect the feeding movements of the tools at the completion of

each rotation of the spindle and gear and, after a plurality of complete revolutions of the spindle, to discontinue operation of the machine.

Another object of the invention is to provide blank-positioning means to properly locate the blank on the spindle so that opposite sides of different teeth may be finished simultaneously by opposed tools. Also associated with this blank positioning means is an interlock mechanism preventing starting of the machine when the positioning means is in engaged position, and preventing movement of the positioning means to its engaged position during normal operation of the machine.

With these and other objects in view, our invention consists in the features of construction and operation set forth in the following specification and illustrated in the accompanying drawings.

In the accompanying drawings annexed hereto and forming a part of this specification, we have shown our invention embodied in an automatic gear shaving machine adapted for rapid production of duplicate spur gears, but it will be understood that the invention can be otherwise embodied and that the drawings are not to be construed as defining or limiting the scope of the invention, the claims appended to this specification being relied upon for that purpose.

In the drawings:

Fig. 15 is a plan view of the stopping mechanism taken on line 15—15 of Fig. 2.

In the above mentioned drawings, we have shown but one embodiment of the invention which is now deemed preferable, but it is to be understood that changes and modifications may be made within the scope of the appended claims without departing from the spirit of the invention.

Briefly, and in its broadest aspect, our invention comprises the following principal parts: First, a base; second, a sleeve rotatably mounted in fixed bearings provided in the base; third, means to oscillate said sleeve through a predetermined adjustable angle; fourth, a work supporting spindle rotatably mounted within said sleeve; fifth, means to index said work supporting spindle relative to the sleeve while the sleeve is oscillating and lock the spindle in indexed position; sixth, a cam fixed to and oscillating with said sleeve; seventh, a slide mounted on the base reciprocated by oscillatory movement of said sleeve and cam; eighth, oppositely disposed tool heads mounted on said slide and movable thereon toward and from each other; ninth, cam means to effect movements of said tool heads to effect feeding movements thereof relative to a gear on said work supporting spindle; tenth, means to actuate the tool feeding means after each complete rotation of the spindle and blank; eleventh, means to stop operation of the machine after a predetermined cycle of operations; twelfth, means to separate the tools from the blank when they have completed their cutting movement; thirteenth, positioning means for the blank

for correctly disposing the blank angularly relative to the spindle; and fourteenth, interlocking mechanism between the positioning means and the operating means for the machine.

Referring more in detail to the figures of the drawings, we provide a base 10 having two fixed bearings 11 therein. Adapted to freely oscillate within these bearings 11 is a hollow spindle or sleeve 12. To oscillate the sleeve an arm 13 is suitably secured thereto, its outer end being attached to a connecting rod 14. The opposite or lower end of the connecting rod 14 engages a crank pin 15 adjustably secured upon one face of a gear 16. Rotation of the gear 16 which is keyed directly to a horizontal driving shaft 17 will therefore oscillate the sleeve 12, the angular or oscillatory movement of the sleeve 12 depending upon the radial position of the crank pin 15 in the gear 16.

To rotate the gear 16 and its shaft 17, which preferably are disposed within the lower part of the base 10, a motor 18 is provided. This motor 18, through suitable reducing gears 19 and an intermediate shaft 20, drives a pinion 21 on sleeve 22 engaging teeth formed on the periphery of the gear 16 carrying the crank pin 15. On the intermediate shaft 20 for driving the pinion 21 is a friction clutch 23, one member of which is on shaft 20 constantly rotated by the motor 18 and the other member is keyed to the sleeve 22. The pinion 21 is keyed or otherwise secured directly to the sleeve 22. A second clutch of the friction type 24 has one member rotating with the sleeve 22 and its companion member is maintained against rotation preferably by being fixed rigidly to a part of the base 10. This clutch 24 when its members are in engaged position acts as a brake to stop rotation of the sleeve 22 and gear 16.

The friction clutches 23 and 24 are operated by a central member 25 movable on the sleeve 22 by a yoke member 26 keyed to a shaft 27 mounted within the base 10. The outer end of this shaft 27 is provided with an upwardly extending lever 28. This lever 28 by means of a suitable connecting rod is attached to a hand lever 29 pivotally mounted on the outside of the base 10. From the above description it will be seen that movement of the hand lever 29 to one operative position will engage friction clutch 23 to rotate the pinion 21 and thus oscillate the sleeve 12. Movement of the lever 29 to its opposite operative position will engage friction clutch or brake 24 and thus quickly bring the machine to rest.

Within the hollow spindle or sleeve 12 is a work supporting spindle 30 to which a gear W to be finished is adapted to be attached in any preferred manner as by means

of the collet chuck 31 shown in Fig. 3. Adjacent the work securing means and surrounding the forward end of this spindle 30 is mounted a large cam 32. This cam 32 is attached rigidly to the sleeve 12 but in a manner permitting ready substitution of different cams for different forms of tooth curves and sizes of gears being finished. A typical form of this cam 32 is best shown 5 in Fig. 5. It will be seen from this figure that there are two oppositely disposed cam portions. The particular contour of these cam portions will vary with the characteristics of the gear W being finished but in 10 each instance the cam is so designed that the distance between points on these cam portions simultaneously engaged by rollers on the tool slide will be equal.

Means to index the work supporting spindle 30 within and relative to the sleeve 12 are provided adapted to angularly advance or rotate the work spindle 32 and gear W relative to the sleeve 12 to permit operation successively upon each of the gear teeth being finished. This indexing means operates 25 during the oscillating movements of the spindle 30 and sleeve 12 and will presently be described.

Mounted in suitable horizontal ways 33 30 extending transversely on a member 34 secured to the upper surface of the base 10 adjacent the forward end of the work spindle 30 is a slide 35. This slide 35 is movable within the ways 33 which are disposed below and at right angles to the axis of the sleeve 12 and work spindle 30. Near the opposite ends of the slide are provided opposed heads 36 which are adjustable within slight limits along the slide 35 and adapted 40 to be rigidly secured thereto in any adjusted position. On the heads 36 are mounted rollers 37 oppositely disposed and adapted to contact with the periphery of the cam 32 on the sleeve 12. Each cam 32 for the 45 sleeve 12 is so designed that during oscillation of the sleeve 12 and the work supporting spindle 30 it is simultaneously engaged by the rollers 37 in all of its oscillated positions. Oscillatory movement of the sleeve 50 12 and spindle 30 and engagement of the cam 32 with the rollers 37 on the slide 35 produces reciprocatory movement of the slide 35 in timed relation to oscillations of the sleeve 12 and gear W being finished.

55 Also mounted on the slide 35 are oppositely disposed tool holding heads 38 mounted for slide movement toward and from each other. For that purpose the tool holding heads 38 are mounted in ways 39 provided 60 on the slide 35 extending parallel to the ways 33 and the ways for the slide 35. The heads 38 have tool supporting devices adapted to hold straight edged upwardly and obliquely extending tools 40 respectively at their inner 65 ends. The tools 40, as shown in Fig. 4, are

oppositely disposed so that they are adapted to engage and cut opposite sides of gear teeth on the blank W. As the gear W and its spindle 30 are indexed between each complete oscillatory movement of the sleeve 12 the gear teeth will all be in contact with and will be cut by the tools 40 during a complete revolution of the work spindle 30. The tools 40 engage the gear teeth near the extreme oscillated positions of the cam 32 and spindle 30. At the extreme oscillated points of oscillation of the spindle 30 and sleeve 12 the tools 40 have completed their cutting movement and upon reversal of the spindle and sleeve move away from the gear teeth. During the 70 mid portions of the oscillatory movements of the sleeve 12 and spindle 30 both of the tools 40 are free from the gear W being finished. At this mid portion of the oscillatory movement of the spindle 30 and sleeve 12 75 while these parts are moving in one direction the indexing mechanism operates to index the spindle 30 relative to the sleeve 12 to present successive or adjacent teeth to the tools upon the following oscillation.

80 As it is desirable to take successive cuts upon each of the gear teeth, means are provided to advance the tools 40 a very slight distance at the end of complete revolutions of the spindle 30 and gear W being finished. 85 In the present embodiment of the invention the gear W being finished is adapted to be indexed through four complete revolutions and its tooth curves are engaged by and cut by the tools 40 upon each revolution of the 90 gear. On the slide 35 at its opposite ends are mounted forwardly and horizontally extending shafts 41. On these shafts 41 are mounted peripheral cams 42, their cam contours being in contact with the outer ends 95 of screws 43 threaded into the tool holding heads 38. Rotation of the cams 42 will therefore advance the tool holding heads 38 towards each other against the pressure of springs 44 normally holding the tool heads 38 as far apart as possible. The shafts 41 carrying the feed cams 42 are adapted to be rotated simultaneously and are for that purpose provided at their forward ends with 100 sprocket wheels 45 over which a chain 46 passes. Rotation of one shaft 41 will therefore rotate the other in timed relation thereto.

105 To rotate the feed cams 42 slowly and in a step-by-step manner at the end of each rotation of the spindle 30 the shaft 41 on the right side is provided at its rear end with a gear 47. This gear 47 as the slide 35 moves toward the right engages a tooth 48 formed on a plate secured to the free end of a horizontal arm 49 mounted for oscillation about a vertical axis. By striking the tooth 48 the gear 47 and shaft 41 are thus rotated through a small angle thus rotating the feed cams 42 a similar amount. The arm 49 is held out 110 of the path of movement of the gear 47 except 115

when feeding movement of the tools 40, at the end of each rotation of the gear W, is required. In order to oscillate the arm 49 to effect rotation of the feed cams for the tools at the completion of each rotation of the gear W being finished the main drive shaft 17 has keyed thereto a small crank 50. To the crank 50 is attached a connecting rod 51, the opposite end of which is attached to an oscillating lever 52 carrying a pawl 53. Rotation of the main shaft 17 will therefore oscillate the pawl 53 which engages the teeth of a ratchet wheel 54 and causes the ratchet wheel 54 to be advanced one tooth for each rotation of the main shaft 17. A ratchet wheel 54 is used having as many teeth as the gear W being finished so that one complete rotation of the ratchet wheel 54 will take place upon a complete rotation of the gear W being finished. The ratchet wheel 54 is on the forward end of a shaft 55 carrying a disk 56 having a notch 57 in its periphery. Rotation of the disk 56 therefore allows the arm 49 on a shaft 59 to be oscillated by a spring 60 when the notch 57 is rotated to a position opposite a small lever 58 on the lower end of the vertical shaft 59 to which the arm 49 is fastened. As soon as the slide 35 starts its movement toward the left the arm 49 is swung out of engagement with the gear 47 so that the gear 47 and shaft 41 are not reversed. By these means the cams 42 are slowly rotated and thus advance the tools 40 to successively advanced cutting positions. As shown in Fig. 5 the feed cams 42 have two series of peripheral portions of successively increased radius. During a half rotation of these cams which takes place during the complete operation upon a gear the tools 40 will be advanced to four different advanced positions.

To properly position the gear W to be finished on the spindle 30 so that the sides of the gear teeth will be engaged by the tools 40 a special positioning device is employed. This comprises a vertically movable plunger 61 suitably mounted within the slide 35 and having a forked upper end adapted to engage opposite sides of a gear tooth on the gear W. A spring 62 normally holds the plunger 61 downward and it is adapted to be forced upward by a rod 63 having rack teeth along one side engaging a segment of a gear 64 on a forwardly extending shaft 65. As the plunger 61 moves laterally during reciprocatory movement of the slide 35 the lower end of the plunger 61 has a nut 66 secured thereto adapted to engage over the inturned ends of a yoke 67 on the upper end of the rod 63 vertically slidable within a fixed portion of the base 10. In the central position of the slide 35 the lower end of the plunger 61 is within the yoke 67 so that it may be raised by the rod 63 and the forwardly extended shaft 65. To actuate the shaft 65 to force the

plunger 61 upward a hand lever 68 is provided on the shaft 65 at its forward end. This lever 68 is connected by means of a spring and rod to a lever 69 on the forward end of shaft 65.

As the machine can not be started with the plunger 61 in its upper and engaged position and the plunger 61 cannot be raised during operation of the machine, interlocking means are provided disposed between the operating lever 29 for the machine and the plunger operating lever 69. On the operating lever 29 is a short arm to which vertically movable link 70 is attached, the opposite end of which is slotted. A stud fastened in the base 10 engages the slot and thus permits sliding movement of the link 70. A bar 71 pivotally connected to the lever 69 on the forward end of the shaft 65 for actuating the plunger 61 is supported at its opposite end for horizontal slidable movement when the shaft 65 is oscillated. The outer end of the bar 71 extends into the path of movement of the link 70 operated by the operating lever 29 when the plunger 61 is in its upper position. The operating lever 29 therefore cannot be operated. When the plunger 61 is down and the operating lever 29 is oscillated to start the machine the link 70 extending past the path of movement of the bar 71 prevents the plunger 61 being raised.

In order to index the work spindle 30 to present the gear teeth of the gear W being finished successively to the tools 40 without loss of excess time, the indexing motion of the spindle 30 is effected during the oscillatory movement of the spindle 30 and its sleeve 12. During the mid portion of the oscillatory movement of the sleeve 12 and work spindle 30 both of the tools 40 are entirely free from the gear W being finished. It is during this portion of the cycle of operations that the indexing is effected. As the spindle 30 and sleeve 12 are oscillating in one direction and reach substantially their mid position the spindle 30 is moved angularly relative to the sleeve 12 an amount to present successive teeth to the tools 40. While the sleeve 12 and spindle 30 are oscillating in the opposite direction a part of the indexing mechanism is moved to a position so that no indexing of the spindle takes place.

To effect the indexing movements while the spindle 30 is being oscillated in one direction but not in the opposite direction the indexing and spindle locking cams are mounted on a swinging frame 75 mounted within the base 10. To oscillate this frame 75 a drum cam 76 is mounted on a shaft 77 in alignment with the shaft 17 on which the gear 16 is mounted. A crank arm 78 connected to the eccentric pin 15 is keyed to the shaft 77 at one end so that the cam 76 is rotated at the same speed as the gear 16. The cam 76 is provided on its periphery with a groove as shown in Fig. 2 so

that with each rotation of the cam 76 a downwardly extended arm 79 keyed to the shaft 81 is oscillated back and forth. A roll 80 formed on this arm 79 engages the groove in the cam 76. The frame 75 is keyed to the shaft 81 so that the frame 75 oscillates back and forth in timed relation to rotation of the gear 16. On the upper end of this frame 75 are mounted the cams 83, 97 and 97^a controlling the indexing and locking of the spindle 30.

Keyed to the spindle 30 is an index plate 84 having spaced notches 85 cut into its periphery corresponding in number to the number of teeth in the gear W being finished. One of these notches 85 is engaged during the cutting periods of the oscillatory motion of the spindle 30 by a locking bolt 86 on a plate 87 slideable radially in an arm 88 carried by and oscillating with the sleeve 12. While the plunger or bolt 86 is in one of the notches 85 of the index plate 84 the work spindle 30 will be oscillated with the sleeve 12. The cutting action of the tools 40 takes place during the portions of the oscillatory movement of the sleeve 12 and spindle 30 while this locking bolt 86 is engaged within a notch 85. To withdraw the locking bolt 86 from the notch 85 the inner end of the member 87 carrying the bolt 86 is provided with a roller 89 entering a small cam groove 90 in a plate 91 surrounding and freely rotatable on a hub formed on the plate 88. Angular movement of this plate 91 to effect disengaging and engaging movement of the bolt 86 is effected by a slideable bar 92 in the arm 88 having rack teeth engaging gear teeth on the plate 91. Movement of the bar 92 to disengage the bolt 86 is obtained by contact with the cam 83 on the swinging frame 75 by a roller 93 on the lower end of the bar 92. Movement of the bar 92 in a direction to engage the bolt 86 in a notch 85 is accomplished by means of a helical spring 94. One end is fast to the arm 88 and the other end to a stud on the bar 92 extending through an elongated notch in the arm. The cam 83 by which the bar 92 is moved upward is positioned and formed so that it will unlock the bolt just before the indexing movement of the spindle takes place and will permit locking movement of the bolt as soon as the indexing is complete and before the spindle 30 is oscillated far enough for the opposite tool 40 to engage another gear tooth. Fig. 9 shows the position of the spindle locking mechanism during that portion of the spindle oscillation during which the indexing is taking place.

The means to index the spindle 30 relative to the sleeve 12 comprise the following mechanism separately shown in Fig. 8. This mechanism is mounted on the sleeve and cooperates with cams mounted on the swinging frame. The arm 88 previously referred to in connection with the operation of the locking bolt has an arm 95 rotatably mount-

ed upon its hub. This latter arm 95 carries a pivotally mounted pawl 96 engaging at its outer end a notch 85 in the index plate 84. Movement of this pawl 96 while engaged in a notch 85 by oscillating movement of the arm 95 relative to the sleeve 12 and the arm 88 fast thereon advances the spindle 30 and the gear W to a new indexed position. This movement of the pawl 96 takes place while the sleeve 12 is in approximately mid position and is effected by a cam 97 on the swinging frame 75. A lever 98 pivotally mounted on the arm 88 about stud 99 has a roller 100 at its outer end contacting with the cam 97 when the swinging frame 75 is in one of its oscillated positions. The opposite end of the lever 98 is slotted and adjustably attached to an adjustable reach arm 101, the opposite end of which is attached adjustably to an arm 102 pivoted about the axis of the pawl 96. A spring 103 surrounding the pivot of the lever 98 normally holds the pawl 96 toward its outer position against a stop 104 formed on the arm 95, a pin 105 on the lever 102 bearing against the stop when the pawl is in its outer position. As the parts on the sleeve 12 are moving in the direction indicated by the arrow in Fig. 8 but before reaching the position shown in Fig. 6 the roller 100 rides up the cam 97 and oscillates the members 98, 101, 102 and pawl 96, and, with the pawl 96 engaged in a notch 85 of the index plate 84 forces the arm 95 carrying the pawl 96 to move relative to the sleeve 12 and thus index the spindle 30. The first movement of the lever 98 contacting with the cam 97 oscillates lever 102 about the center forming the pivot for the indexing pawl 96 and this forces the pawl 96 into a notch 85. As soon as the pawl 96 has engaged a notch 85 the pawl 96 and its arm 95 are rotated about the axis of the sleeve 12. By adjusting the pivotal connections at the ends of the connecting rod 101 this movement of the arm 95 and the pawl 96 which rotates the index plate 84 can be widely adjusted.

To prevent the tools 40 dragging over the finished surfaces of the gear teeth on the oscillatory movement of the spindle 30 and gear W during the first portions of their arcs of movement, means are provided to very slightly oscillate the spindle 30 at the extreme end of its oscillatory movement in a direction to slightly separate the engaged tool 40 from the gear W. This movement takes place before the slide 35 carrying the tools 40 starts on its rearward path. An arm 106 keyed to the sleeve 12 and preferably forming the support for the arm 88 is provided with adjustable abutments 107 between which the arm 88 may move very slightly. This movement of the arm 88 together with the locking bolt 86 and associated parts permits a correspondingly slight angular movement of the spindle 30 and gear W. In order to move the arm 106

88 from one adjustable stop or abutment 107 to the other at the extreme oscillated positions of the cam 32 and spindle 30 a lever 108 is pivotally mounted on the arm 106, its outer end being adapted to engage abutments 109 secured rigidly to the frame or base 10 of the machine and suitably spaced apart. This is shown in Fig. 7 from which it will be evident that at each limit of oscillation of the sleeve 12 and parts oscillating therewith the lever 108 will be oscillated about its pivot in one or the other direction. Pivotal movement of the lever 108 moves a slidable member 110 retained in the arm 106, this movement being effected by means of gear teeth formed on an arm of the lever 108 and on the slidable member 110. The slidable member 110 is disposed radially of the plate 106 and is connected to a slidable member 111 in the arm 88 by a pin 112. By means of this pin connection 112 between the slidable members 110 and 111 the members 110 and 111 may be moved angularly relative to each other. The member 112 is disposed within the arm 88 slightly obliquely relative to radial lines so that movement of the members 110 and 111 inward and outward will angularly move the arm 88 relative to the member 106 fast on the sleeve 12. The movement of the arm 88 relative to member 106 is limited by the abutment 107 which may be slightly adjusted.

The abutments 109 are resiliently forced forwardly within casings 113 by springs 114 and when forced inwardly take up positively against shoulders 116. With the sleeve 12 and spindle oscillating in the direction shown by the arrow in Fig. 7 when the lever 108 reaches the abutment 109 it forces the abutment 109 inward and when this abutment takes up against the shoulder 115 the lever 108 is oscillated slightly. This slight movement of the lever 108 releases the sliding blocks 110 and 111 from their locked position with the member 106 forced toward one of the stops 107 on member 88. The abutment 109 then springs outward and oscillates the lever 108 to force the sliding members 110 and 111 to their opposite position. This relatively moves the member 106 angularly of the member 88 and rotates the spindle in a direction to separate the gear W from the engaged tool 40.

To stop operation of the machine when the gear W being operated on has been completely finished, means are provided to move the main starting lever 29 to its inoperative position. On the shaft 55 carrying the notched disk 56 is a pinion 117 engaging a gear 118 of larger size on a short shaft 119 below the shaft 55. The ratio between the gears 117 and 118 is equal to the number of complete rotations of the gear W being finished required while being operated on by the tools 40. The shaft 119 will therefore make one complete rotation during the cycle of operations of the machine. On the for-

ward end of this shaft 119 is a disk 120 having a projection 121 extending from its rear face. When operations on the gear have been completed this projection 121 forces a bolt 122 rearward against a spring by means of rod 123. Movement of this bolt 122 releases a spring pressed lever 124 on the shaft 125 to which the main operating lever 29 is keyed so that this lever 29 is moved to its inoperative position, thus stopping the machine. The position of the parts shown in Fig. 2 is that after the lever 29 has been moved to inoperative position. Movement of the lever 29 to start the machine resets the bolt 122 and member 124. A detent 126 having two notches resiliently retains the operating lever 29 in its operative and inoperative positions by engagement with the notches of a small plunger 127. The detent 126 is rotatably mounted adjacent the member 124 and is angularly moved by movement of the lever 124 through a pin 128 on the detent being engaged by the sides of a notch formed in a plate 130 secured to the lever 124.

To facilitate manual operation of the machine during preliminary adjustments, the shaft 17 is provided with a sprocket wheel 131 over which passes a chain 132. This chain 132 passes over a smaller sprocket wheel 133 on a shaft or stud 134 conveniently located on the front of the machine. A hand wheel 135 keyed to rotate with the sprocket wheel 133 enables an operator to slowly rotate the shaft 17 and thus actuate the mechanism of the machine.

To adjust the machine for different diameters of gears W the thickness of the member 34 carrying the slide 35 may be chosen to position the rollers 37 and tools 40 correctly relatively to the cam 32 and blank W. The amount of oscillation given the sleeve 12 and spindle 30 is adjusted by the crank 15. To control the angular movement of the spindle 30 relative to the sleeve 12 for indexing the blank W the position of the arm 101 is changed. It will be understood also that the index plate 84 will have notches equal to, or a multiple of, the number of teeth to be cut in the blank W. To positively hold the indexing pawl 96 within a notch 85 a roller 96^a may be mounted thereon and adapted to engage during a portion of the oscillatory motion of the sleeve 12 with a cam 97^a on the swinging member 75.

In operation the sleeve 12 is oscillated by rotation of the main drive shaft 17 and the crank pin 15. By means of the cam 32 on the sleeve 12 the tool carrying slide 35 is reciprocated. A gear blank W mounted to oscillate with the sleeve 12 will therefore have its teeth engaged and cut by the tools 40 toward the ends of the oscillatory movement of the sleeve 12 in both directions.

Indexing movement of the gear blank W relative to the sleeve 12 to present successive

- teeth to the tools 40 takes place with the tool slide 35 approximately at its mid-position and while the tools are out of contact with the gear blank. This indexing movement is 5 accomplished by the mechanism shown in Figs. 6 et seq. In order that indexing movements may not take place on each oscillatory movement of the sleeve 12 the actuating mechanism comprising the cams carried by the 10 swinging frame 75 are moved into and out of operative position in timed relation with the oscillatory movement of the sleeve 12. This is accomplished by the cam 76 rotated by the main drive shaft. With the frame 75 15 in its inoperative position the sleeve 12 oscillates from one extreme position to the other without indexing the gear blank and its spindle 30. On the reverse oscillatory movement of the sleeve 12 the frame 75 is moved into 20 operative position so that the spindle 30 carrying the gear blank is indexed.
- It will be understood that the gear blank 25 consists of a partially formed gear, the teeth being roughed out to approximate form. The cutting action of the tools 40 which takes 30 place in the direction of the roll of the gear acts to shave the contour of the gear faces to correct and finished form. When the indexing movement of the spindle 30 and blank 35 W has been completed about the sleeve 12, each of the gear teeth will have been engaged by the tools 40. It is preferred, however, to cut the teeth upon several successive indexing movements of the blank W. As soon 40 as a complete indexing movement of spindle and blank takes place the feed cams 42 are rotated through a portion of a revolution so that each successive rotation of the blank will serve to cut the teeth additional amounts.
- When several complete indexing movements have taken place, the mechanism is stopped preparatory to removing the finished gear and mounting another blank in position.
- What we claim is:
- 45 1. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces engaging a gear on said spindle during the movement of said spindle and slide, whereby oppositely disposed tools alternately engage said gear upon each oscillation of said spindle, and means to index said spindle, and means to advance said tool heads to successive operative positions.
- 50 2. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces, whereby oppositely disposed tools alternately engage said gear upon each oscillation of said spindle, means to index said spindle, and means to advance said tool heads to successive operative positions after each complete rotation of the spindle.
- 55 3. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces engaging a gear on said spindle during the extreme oscillated positions of said spindle and cam, whereby oppositely disposed tools alternately engage said gear upon each oscillation of said spindle, and indexing means for said spindle operative during the mid-portions of the oscillatory movements of said spindles.
- 60 4. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces engaging a gear on said spindle, whereby oppositely disposed tools alternately engage said gear upon each oscillation of said spindle, and indexing means for said spindle operative during oscillation of said spindle and while said tools are out of engagement with said gear.
- 65 5. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces, whereby oppositely disposed tools alternately engage said gear upon each oscillation of said spindle, means to index said spindle, and means to advance said tool heads to successive operative positions.
- 70 6. A gear finishing machine comprising in combination, a base, a gear supporting spindle mounted for oscillation on a fixed axis thereon, a cam on said spindle adapted to be actuated therewith, a slide on said base reciprocated by said cam while said spindle is oscillating, tool heads on said slide on opposite sides of the blank axis and having tools provided with cutting edges upon their end faces arranged in opposed relation

to each other and adapted to engage opposite sides of teeth on the gear on said spindle, and means to advance said tool heads to successive operative positions.

- 5 7. A gear finishing machine comprising in combination, a base, a gear supporting spindle mounted for oscillation on a fixed axis thereon, a cam on said spindle adapted to be actuated therewith, a slide on said base 70 mounted for movement below and at right angles to said spindle reciprocated by said cam while said spindle is oscillating, tool heads on said slide on opposite sides of the blank axis and having tools thereon provided with cutting edges upon their end faces, whereby oppositely disposed tools alternately engage said gear upon each oscillation of said spindle, means to index said spindle, and means to advance said tool heads to successive operative positions.

- 10 8. A gear finishing machine comprising in combination, a base, a gear supporting spindle mounted for oscillation on a fixed axis thereon, a cam on said spindle having opposed cam surfaces so disposed that distances between points in said cam surfaces upon a tangent to a circle coaxial with its axis of oscillation are equal, a slide on said base having rollers thereon contacting with opposite sides of said cam and reciprocated by said cam while said spindle is oscillating, tool heads on said slide on opposite sides of the blank axis and having tools thereon provided with cutting edges upon their end faces, whereby oppositely disposed tools alternately engage said gear upon each oscillation of said spindle, and means to advance said tool heads toward each other at the completion of each rotation of said spindle.

- 15 9. A gear finishing machine comprising in combination, a base, a gear supporting spindle mounted for oscillation on a fixed axis thereon, a sleeve surrounding said spindle, means to oscillate said spindle and sleeve through predetermined angular distances, means to index said spindle relative to said sleeve during oscillatory movement of said spindle and sleeve, a cam on said sleeve adapted to be actuated therewith, a slide on said base reciprocated by said cam while said spindle and sleeve are oscillating, and tool heads on said slide having cutting tools thereon provided with cutting edges upon their end faces disposed to engage opposite sides of different teeth.

- 20 10. A gear finishing machine comprising in combination, a base, a gear supporting spindle mounted for oscillation on a fixed axis thereon, a sleeve surrounding said spindle, means to oscillate said spindle and sleeve through predetermined angular distances, means to index said spindle relative to said sleeve during oscillatory movement of said spindle, a cam on said sleeve adapted to be actuated therewith, a slide on said base dis-

posed below and movable at right angles to the axis of said spindle and reciprocated by said cam while said spindle and sleeve are oscillating, and tool heads on said slide having tools thereon provided with cutting edges upon their end faces having cutting tools thereon disposed to engage opposite sides of different teeth.

- 25 11. A gear finishing machine comprising in combination, a base, a gear supporting spindle mounted for oscillation on a fixed axis, a sleeve surrounding said spindle, means to oscillate said spindle and sleeve through predetermined angular distances, means to index said spindle relative to said sleeve during oscillatory movement of said spindle and sleeve, a cam on said sleeve adapted to be actuated therewith, a slide transversely movable on said base reciprocated by said cam while said spindle and sleeve are oscillating, and tool heads adjustably mounted on said slide and having cutting tools thereon provided with straight cutting edges upon their end faces and disposed to engage opposite sides of different teeth.

- 30 12. A gear finishing machine comprising in combination, a base, a gear supporting spindle mounted for oscillation on a fixed axis thereon, a sleeve surrounding said spindle, means to oscillate said spindle and sleeve through predetermined angular distances, means to index said spindle relative to said sleeve during oscillatory movement of said spindle and sleeve, a cam on said sleeve adapted to be actuated therewith, a slide on said base reciprocated by said cam while said spindle and sleeve are oscillating, tool heads on said slide having cutting tools thereon provided with cutting edges upon their end faces disposed to engage opposite sides of different teeth, and means to simultaneously advance said tools to successive operative positions.

- 35 13. A gear finishing machine comprising in combination, a base, a gear supporting spindle mounted for oscillation on a fixed axis thereon, a sleeve surrounding said spindle, means to oscillate said spindle and sleeve through predetermined angular distances, means to index said spindle relative to said sleeve during oscillatory movement of said spindle, a cam on said sleeve adapted to be actuated therewith, a slide on said base disposed below and movable at right angles to the axis of said spindle and reciprocated by said cam while said spindle and sleeve are oscillating, tool heads on said slide having cutting tools thereon provided with cutting edges upon their end faces disposed to engage opposite sides of different teeth, of the gear on said spindle, and means to advance said tool heads toward each other to successive operative positions upon each successive rotation of said spindle.

- 40 14. A gear finishing machine comprising

- in combination, a base, a gear supporting spindle mounted for oscillation on a fixed axis, a sleeve surrounding said spindle, means to oscillate said spindle and sleeve through predetermined angular distances, means to index said spindle relative to said sleeve during oscillatory movement of said spindle, a cam on said sleeve adapted to be actuated therewith, a slide on said base reciprocated by said cam while said spindle and sleeve are oscillating, opposed tool heads on said slide having cutting tools thereon provided with cutting edges upon their end faces disposed to engage opposite sides of different teeth, and cam means on said slide to advance said tool heads to successive operative positions. 15. A gear finishing machine comprising in combination, a base, a gear supporting spindle mounted for oscillation on a fixed axis, a sleeve surrounding said spindle, means to oscillate said spindle and sleeve through predetermined angular distances, means to index said spindle relative to said sleeve during oscillatory movement of said spindle and sleeve, a cam on said sleeve adapted to be actuated therewith, a slide transversely movable on said base reciprocated by said cam while said spindle and sleeve are oscillating, tool heads adjustably mounted on said slide and having cutting tools thereon provided with straight cutting edges upon their end faces and disposed to engage opposite sides of different teeth, and means to advance said tool heads to successive operative positions. 20. A gear finishing machine comprising in combination, a base, a sleeve mounted for oscillation therein, a work supporting spindle coaxial within said sleeve, means to oscillate said sleeve, index means mounted on said sleeve and work supporting spindle whereby said work supporting spindle may be indexed relative to said sleeve, and means positioned to effect indexing movement of said work supporting spindle relative to said sleeve while said spindle is rotating in one direction, said last mentioned means being moved to inoperative position during rotation of said spindle and sleeve in the opposite direction. 25. A gear finishing machine comprising in combination, a base, a sleeve mounted for oscillation therein, a work supporting spindle coaxial within said sleeve, means to oscillate said sleeve, index means mounted on said sleeve and work supporting spindle whereby said work supporting spindle may be indexed relative to said sleeve, means positioned to effect indexing movement of said work supporting spindle relative to said sleeve while said spindle and sleeve are rotating in one direction, and cam means to move said last mentioned means to inoperative position when said spindle and sleeve are moving in the opposite direction. 30. A gear finishing machine comprising in combination, a base, a sleeve mounted for oscillation therein, a work supporting spindle coaxial within said sleeve, means to oscillate said sleeve, index means mounted on said sleeve and work supporting spindle whereby said work supporting spindle may be indexed relative to said sleeve, a swinging frame, cams on said frame coacting with said means on said sleeve and spindle to effect said indexing movements, and means to move said swinging frame into and out of operative position in timed relation to the movements of said sleeve and spindle. 35. A gear finishing machine comprising in combination, a base, a sleeve mounted for oscillation therein, a work supporting spindle coaxial within said sleeve, means to oscillate said sleeve, index means mounted on said sleeve and work supporting spindle whereby said work supporting spindle may be indexed relative to said sleeve, a gear supporting spindle mounted for oscillation on a fixed axis thereon, opposed tools slidably mounted on said base and adapted to engage a gear on said spindle during oscillatory movements of said spindle, and means to slightly rotate the spindle at the opposite ends of its oscillatory motion to free the tools from contact with the gear during retrograde movement of the tool over the gear.

23. A gear finishing machine comprising in combination, a base, a gear supporting spindle mounted for oscillation on a fixed axis thereon, opposed tools slidably mounted on said base, means to oscillate said spindle and reciprocate said tools to engage a gear on said spindle as the spindle approaches its extreme oscillated positions, and means to slightly rotate said spindle in a direction to free the gear from a tool as soon as the spindle is oscillated to its extreme position.
24. A gear finishing machine comprising in combination, a base, a gear supporting spindle mounted for oscillation on a fixed axis thereon, opposed tools slidably mounted on said base, means to effect sliding movements of said tools in timed relation to oscillatory movements of said spindle, and means to slightly oscillate said spindle at its extreme oscillated positions in a direction to return the spindle to its central position before said tools are moved in the opposite direction.
25. A gear finishing machine comprising in combination, a base, a gear supporting spindle mounted for oscillation on a fixed axis thereon, a sleeve surrounding said spindle, means to oscillate said sleeve, opposed tools slidably mounted on said base, means to effect sliding movements of said tools in timed relation to oscillatory movements of said sleeve, an index plate on said spindle adapted to be engaged by a locking bolt, a support for said locking bolt mounted on said sleeve, and means to slightly move said support relative to said sleeve at the opposite ends of the oscillatory movement of said spindle and sleeve.
26. A gear finishing machine comprising in combination, a base, a gear supporting spindle mounted for oscillation on a fixed axis thereon, a sleeve surrounding said spindle, means to oscillate said sleeve, opposed tools slidably mounted on said base, means to effect sliding movements of said tools in timed relation to oscillatory movements of said sleeve, an index plate on said spindle adapted to be engaged by a locking bolt, a support for said locking bolt mounted on said sleeve, abutments on said base adjacent said base, and means oscillating with said sleeve and engaging said abutments to slightly move said support relative to said sleeve at the opposite ends of the oscillatory movement of said spindle and sleeve.
55. In testimony whereof, we hereto affix our signatures.

HUBERT D. TANNER.
